UNITED STATES PATENT OFFICE.

OSCAR WOODWARD, OF MONTCLAIR, NEW JERSEY, ASSIGNOR TO YOST WRITING MACHINE COMPANY, OF ILION, NEW YORK, A CORPORATION OF NEW YORK.

TYPE-WRITING MACHINE.

No. 893,829.

Specification of Letters Patent.

Patented July 21, 1908.

Application filed March 23, 1908. Serial No. 422,709.

To all whom it may concern:

Be it known that I, OSCAR WOODWARD, citizen of the United States, and resident of Montclair, in the county of Essex and State of New Jersey, have invented certain new and useful Improvements in Type-Writing Machines, of which the following is a specification.

My invention relates to typewriting machines and more particularly to means operable at will for maintaining the types out of contact with the inking pad to facilitate the removal from and the introduction of an ink pad into the machine.

15 The present invention is in the nature of an improvement on the construction disclosed in my prior application Serial No. 357,609. In that construction and in all prior constructions, so far as I am aware, the 20 type bars are all simultaneously moved away from the ink pad and all of the type bars are given the same extent of movement. For these reasons the type bars may be given but a very slight movement away from the ink 25 pad without being brought into conflict.

The main object of my present invention is to overcome the above difficulties and to provide simple and efficient means for moving the type bars away from the ink pad a sufficient distance to enable it to be readily removed from the machine and without bringing the type bars into engagement with one another.

To the above and other ends which will 35 hereinafter appear, my invention consists in the various features of construction, arrangements of parts and combinations of devices to be hereinafter described and particularly pointed out in the appended claims.

40 In the accompanying drawings wherein like reference characters indicate corresponding parts in the different views, Figure 1 is a fragmentary central vertical front to rear sectional view showing a sufficient number 45 of parts of one form of typewriting machine to illustrate my invention, the view illustrating the parts in the normal position with the locking bar or plate in the inoperative position. Fig. 2 is a like view of the same 50 with some of the parts omitted and with the locking bar in the operative position. Fig. 3 is an enlarged detail fragmentary vertical sectional view showing a portion of the locking mechanism. Fig. 4 is a detail fragmentary

front elevation of the means for locking the 55 key levers depressed.

While I have illustrated my invention applied to a front strike typewriting machine embodying a type action of the same specific character as that disclosed in the application 60 of George F. Ballou filed January 22, 1907, Serial No. 353,558 and of the same general character as that shown in the application of Arthur W. Smith filed May 15, 1905, Serial No. 260,441, it should be understood that the 65 invention may be applied to other styles of typewriting machines.

The frame of the machine comprises a base 1, corner posts 2 and a top plate 3. Any suitable carriage (not shown) is provided 70 with a platen 4, diagrammatically shown in Fig. 1, the carriage traveling from side to side of the machine in the usual manner. A segment 5 has radially disposed hangers 6 secured thereto by screws 7. Each hanger has 75 a driver 8 pivoted thereto at 9 and each driver is pivoted at 10 to a type bar proper 11. The forward end of each type bar is pivoted at 12 to a guide link 13. The guide links of the system of type bars are pivoted on 80 a pivot wire 14, each guide link being received and guided in a radial slot 15 in a segment 16. A pull link 17 is connected at its rear end 18 to the associated driver 8, the forward end of the link being connected at 19 85 to a bell crank sub-lever 20. The sub-levers are each pivoted at 21 to a hanger 22 secured by a nut 23 to a segment 24. The forwardly projecting arm of each bell crank sub-lever 20 is connected to the upper end of a link 25, 90 the lower end of which is connected at 26 to an associated key lever 27. The key levers 27 are all pivoted on a pivot rod 28 secured to depending arms 29 which form part of a frame comprising segments 5, 16 and 24 al- 95 though for the purposes of the present invention this frame may be regarded as a part of the main frame of the machine. Each key lever is provided with a finger key 30 and an upwardly projecting arm or member 31, 100 which latter is received in a slot 32 formed in a guide or comb-plate 33. The comb-plate forms part of an angular plate 34 secured by screws 35 to brackets 36 which project from the segment 34. Brackets 37 are secured by 105 screws 38 to the angular plate 34 near each side of the machine and are provided with bearings 39 for the reception of a rock shaft

40. This rock shaft is grooved throughout its length to receive a locking or depressor bar or plate 41 which extends substantially throughout the length of the rock shaft and 5 throughout the width of the keyboard as shown in Fig. 4.

The right-hand end of the rock shaft 40 is bent to form a crank arm 42 provided with a finger piece 43 by which the rock shaft may be 10 turned in its bearings to move the locking bar to and from operative position. The inoperative position of the locking or depressor bar is shown in Fig. 1 and the operative position of the bar is shown in Figs. 2 and 4.

15 The locking bar is apertured near the right-hand end thereof at 44 for the reception of the reduced end 45 of a leaf spring 46, the other end of the leaf spring being secured by screws 47 to the under side of the angular plate 34. The construction is such that the 20 tension of the leaf spring is exerted against the upper wall of the slot 44 of the locking bar to maintain said bar in the inoperative position when it is turned to such position

25 through an actuation of the finger piece 43 as indicated in Fig. 3. This same spring likewise bears against the upper wall of the slot when the finger piece is turned to the position shown in Fig. 2 to maintain the locking 30 bar against accidental displacement from the operative position to which it may likewise be moved by the finger piece. The spring at this time exerts a pressure towards the axis of the rock shaft, thus tending to prevent the 35 locking bar from being turned from the operative position. The shoulders 46^a on the spring 46 formed by the reduced portion 45 abut the locking plate 41 at each side of the aperture 44 therein and limit the forward 40 movement of the plate. It will be understood that the types 48 normally bear against an inking pad 49 contained in a case 50 which may be detachably secured to the frame of the machine. The inking pad may 45 likewise be detachably mounted in its trough-like case 50. One inking pad may be removed and another substituted therefor at will either by removing the inking pad from its case or by lifting the case and the inking 50 pad together out of the machine and substituting a new pad for the one which is exhausted.

In order to facilitate the removal of the inking pad it is desirable or necessary to remove all the types 48 from contact with the inking pad. It is for this purpose that the so-called locking bar 41 is provided. When the locking bar is in the inoperative position shown in Fig. 1 the types normally rest on the ink pad and are free to be actuated and to move to the printing position as indicated by the dotted line in Fig. 1 at each depression of the key 30. When it is desired to remove the inking pad the finger piece 43 is moved 60 rearwardly from the position shown in Fig. 1

to that indicated in Fig. 2. The effect of this movement is to turn the locking bar around an axis substantially coincident with one edge thereof and to depress all of the key levers to the positions shown in Fig. 2, thereby 70 moving all of the jointed type bars in radial planes a sufficient distance to carry the types out of contact with the inking pad as shown in Fig. 2 to facilitate a removal of the pad. When a new or re-inked pad has been introduced into the machine the finger piece 43 is again moved to the position shown in Fig. 1, thereby 75 releasing all of the key levers and enabling the types to again contact with the inking pad.

80 From an inspection of Fig. 4 it will be observed that the lower edge of the locking plate 41 is notched as indicated at 41^a in order to provide contact faces which are situated at different distances from the pivotal axis of the locking bar. In the present instance I have shown the locking bar notched so that the bottom walls of the notches co-operate with the associated key lever 27 whereas the projections between the notches 90 in the bar coact with alternate key levers. The object of this arrangement is to enable a group comprising one-half of the key levers to be taken up and moved by the contact faces on the projections of the locking bar 95 before the other group comprising the remaining half of the key levers is taken up and moved by the notched portions of the locking bar. When the locking bar is moved to the operative position the effect of this is to 100 first produce a movement of one-half of the type bars away from the inking pad and to then remove the other half of the type bars away from the inking pad. The two groups of type bars are moved away from the inking 105 pad to different distances as shown in Fig. 2 wherein it will be seen that the upper set of bars which are first moved away from the pad by the projections on the locking bar are moved to a greater extent than the lower set 110 of bars shown in Fig. 2. In this manner the radially disposed bars of the two groups are moved successively away from the inking pad so that there is no conflict between the bars which move in radially disposed planes 115 towards each other.

Various changes may be made without departing from the spirit and scope of my invention.

What I claim as new and desire to secure 120 by Letters Patent is:—

1. In a typewriting machine, the combination of an ink pad, a plurality of type bars normally resting against said ink pad, and hand actuated means operable at will for effecting varying extents of movement of the different type bars away from the inking pad and for holding them away from the inking pad.

2. In a typewriting machine, the combina- 130

tion of an ink pad, a plurality of type bars normally resting against said ink pad, and hand actuated means operable at will for successively moving different groups of the type bars away from the inking pad.

3. In a typewriting machine, the combination of an ink pad, a plurality of type bars normally resting against said ink pad, and hand actuated means operable at will for effecting by a single actuation of said hand actuated means varying extents of movement of the different type bars away from the inking pad and for holding them away from the inking pad.

15 4. In a typewriting machine, the combination of an ink pad, a plurality of type bars normally resting against said ink pad, and hand actuated means operable at will for successively moving different groups of the type bars away from the inking pad and for holding them away from the ink pad by a single actuation of said hand actuated means.

5. In a typewriting machine, the combination of an ink pad, a plurality of type bars normally resting against said ink pad, key actuated devices for said type bars, and a hand controlled movable notched bar co-acting with said key actuated devices.

30 6. In a typewriting machine, the combination of an ink pad, a plurality of type bars normally resting against said ink pad, key levers for said type bars, and a hand controlled movable notched depressor bar co-acting with said key levers.

35 7. In a typewriting machine, the combination of an ink pad, a plurality of type bars normally resting against said ink pad, key actuated devices for said type bars, a hand controlled movable notched bar co-acting with said key actuated devices, and means for holding the notched bar in operative position.

45 8. In a typewriting machine, the combination of an ink pad, a plurality of type bars normally resting against said ink pad, key levers for said type bars, a hand controlled movable notched depressor bar co-acting with said key levers, and means for holding the notched depressor bar in the operative 50 position to maintain the key levers depressed and the type bars away from the ink pad.

55 9. In a typewriting machine, the combination of an ink pad, a plurality of type bars normally resting against said ink pad, and a hand controlled bar pivoted to the frame of the machine and having contact faces at different distances from the pivotal center of said bar for moving the type bars away from 60 the ink pad.

10. In a typewriting machine, the combination of an ink pad, a plurality of type bars normally resting against said ink pad, a hand controlled bar pivoted to the frame of the

machine and having contact faces at different distances from the pivotal center of said bar for moving the type bars away from the ink pad, and means for holding said pivoted bar in either the operative or inoperative position.

65 11. In a front strike typewriting machine, the combination of an ink pad, a plurality of segmentally arranged upwardly and rearwardly striking jointed type bars normally resting against the face of an ink pad, key levers for actuating said type bars, a hand controlled device pivoted to the frame of the machine and having contact faces at different distances from the pivotal center of said device, which contact faces coöperate with 70 all of said key levers to maintain them partly depressed so that the type bars may be maintained off the ink pad, and means for maintaining said device either in or out of coöperative relation with the key levers.

75 12. In a typewriting machine, the combination of an ink pad, a series of type bars normally resting on said ink pad, key levers for said type bars, a locking bar pivoted substantially in line with one edge thereof to the frame of the machine and having a notched contact face coöperative with the key levers of the entire system of type bars to maintain 80 said key levers depressed and the type bars away from the ink pad, and a finger piece for controlling the movement of said bar on its pivotal center into and out of operative relation with said key levers.

85 13. In a typewriting machine, the combination of an ink pad, a series of type bars normally resting on said ink pad, key levers for said type bars, a locking bar pivoted substantially in line with one edge thereof to the frame of the machine and having a notched contact face coöperative with the key levers 90 of the entire system of type bars to maintain said key levers depressed and the type bars away from the ink pad, a finger piece for controlling the movement of said bar on its pivotal center into and out of operative relation 95 with said key levers, and a spring for retaining the locking bar in either the operative or inoperative position.

100 14. In a typewriting machine, the combination of an ink pad, a series of type bars normally resting on said ink pad, key levers for said type bars, a locking bar pivoted substantially in line with one edge thereof to the frame of the machine and having a notched contact face coöperative with the key levers 105 of the entire system to maintain said key levers depressed and the type bars away from the ink pad, a finger piece for controlling the movement of said bar on its pivotal center into and out of operative relation with said key levers, the locking bar having a perforation formed therein, and a leaf spring that 110 extends through said perforation and bears 115 120 125

against the edge thereof and retains the locking bar in either the operative or inoperative position.

15. In a typewriting machine, the combination of an ink pad, a series of type bars normally resting on said ink pad, a series of key levers for actuating said type bars, a rock shaft journaled in bearings in a fixed portion of the machine, a plate fixed to said 10 rock shaft and adapted to depress different key levers of the system different distances when the rock shaft is turned, and a finger

piece connected with said rock shaft and by means of which the plate is moved to the operative or inoperative position.

15

Signed at the borough of Manhattan; city of New York, in the county of New York, and State of New York, this 21st day of March, A. D. 1908.
